MOTOR COMPRESSOR OF THE FREE PISTON
TYPEHermann Jänicke, Dessau (Anhalt), Germany,
assignor to Therese Junkers, Gauting, near
Munich, GermanyApplication October 2, 1935, Serial No. 43,187
In Germany October 16, 1934

9 Claims. (Cl. 230—56)

My invention relates to free piston motor compressors and more especially to that type of engines of the kind aforesaid, in which the air compressed in the compressor is utilized to drive the 5 motor, forming part of the mixture of gas and air, or to scavenge the motor cylinder.

It is an object of my invention to improve this type of motor compressor. In motor compressors, in which the pistons of the motor and the 10 compressor are rigidly connected with each other, forming a freely oscillating mass system, it has been suggested to regulate the compressor output at an approximately constant stroke of the freely moving mass by varying the pressures 15 (the suction pressure or the exhaust pressure or both) prevailing in the compressor. It has also been proposed to feed the compressed air delivered by the compressor, as a whole or partly, to the motor as scavenging and charging air under 20 a comparatively high pressure, the exhaust gases (gases of combustion and scavenging air in excess) being fed to a secondary engine, for instance a piston engine or a turbine, to drive it.

According to this invention now the suction 25 and the delivery pressures in the compressor of an engine of this type are varied for the purpose of regulating the energy developed by the driving gas furnished by the motor, and this in such manner that the ratio between these two pressures (which is hereinafter called the pressure ratio of the compressor) remains at least approximately constant.

This mode of regulation of such motor compressors has the effect that the pressure ratio 35 (scavenging and charging pressure: compression end pressure) remains also at least approximately constant. If for instance the suction pressure in the compressor is reduced, while the pressure ratio of the compressor remains constant, the discharge pressure drops also correspondingly. In consequence of the reduced pressures the feed-back energy liberated by the expansion of the residual compressed air in the dead space of the compressor becomes smaller 40 also during the return stroke; however, since together with the discharge pressure of the compressor also the scavenging and charging pressures (and consequently the quantity) of the motor charge (constant charging volume times 45 density of the charge) had been reduced, the reduced feed-back energy still suffices to compress this reduced quantity of motor charge at about the same pressure ratio as hitherto prevailed in the motor. Since in motors with ignition by compression, as are used as a rule for

driving free piston motor compressors, it is important to reach a predetermined end temperature of the compressed charging air, which, however, mainly depends from the pressure ratio, this possibility of keeping the pressure ratio in 5 the motor at least approximately constant, is of decisive importance for the faultless operation of a free piston motor compressor of this type regulatable within wide limits.

The reduction of the discharge and delivery 10 pressures and in consequence also of the motor pressures under partial loads at the same time leads to a considerable reduction of the number of cycles of action per unit of time, i. e. to a further regulation of output of the engine, so 15 that comparatively small variations of pressure will give rise to considerable variations of the quantity of driving gas delivered.

If the compressor piston has a larger diameter than the motor piston, there is provided on the 20 rear side of the compressor piston a differential surface equal to the difference between the surface of the compressor piston and the surface of the motor piston; the pressure acting on this surface results, during the return stroke, in an 25 amount of energy taken up, by which the energy available during the return stroke for the compression of the motor charge is diminished. Therefore if the amount of the feed-back energy 30 liberated in the compressor varies in consequence 35 of regulating operations, the amount of energy taken up by the rear face of the compressor piston must also be varied in the same sense in order that the amount of energy available for the compression of the motor charge enable this 40 compression to be carried through with the desired pressure ratio which shall be kept approximately constant. Therefore, in accordance with this invention, I further provide that the suction pressure of the compressor which shall be regulated 45 act on the rear face of the compressor piston. This pressure may either act on the piston unvariably as a constant load during the entire stroke or it may form the lower or the higher end pressure of a compression-expansion line.

I will now explain my invention in detail, having reference to the drawings annexed to this specification and forming part thereof, which illustrates in a purely diagrammatic manner an 50 engine embodying my invention by way of example.

In the drawings

Fig. 1 shows a diagrammatic longitudinal section of a free piston motor compressor includ- 55

ing two reciprocating free pistons, being one embodiment of the present invention, while each of the Figs. 2 to 5 shows the pressure-volume-diagrams of the several compression spaces for 5 two regulation conditions.

Fig. 6 is a section of a modified form of a separate control member.

Fig. 7 illustrates diagrammatically a modification being a free piston motor compressor including one reciprocating free piston, while 10

Fig. 8 is a longitudinal section, drawn to a larger scale, through the motor cylinder shown in Fig. 7.

Referring to the drawings, 1 is the motor cylinder, in which operate two pistons 2, 2 moving in 15 opposite directions; each of these motor pistons, one of which controls the scavenging ports 3, the other one the exhaust ports 4, is rigidly connected with the compressor piston 5. The compressor pistons operate in compressor cylinders 6 arranged coaxially to the motor cylinder 1 and provided with suction valves 7 and pressure valves 8.

When the two freely moving masses 2, 5 have 20 approached each other and when the quantity of charging air enclosed between the motor pistons 2 is compressed, fuel is injected into the air through the nozzle 9. The regulation by means of a fuel pump of the quantity of fuel to be supplied to the motor may take place e. g. in a well known manner in dependency of a pressure gas container, as described in detail e. g. in the description of Fig. 1 of applicant's copending U. S. application Ser. No. 710,483. Such container may 25 be connected to conduit 10 after the compressor portion of the free piston engine according to the present invention in a manner such that from this container the scavenging air passes into the motor cylinder. On the other hand, a pressure 30 gas container might also be connected to the conduit 30 so that the secondary engine is supplied from this container. The gases of combustion generated in the combustion, which now 35 sets in, force the freely moving masses apart (working stroke). In consequence thereof there 40 first takes place a compression of the charge enclosed in the compressor cylinders from the pressure p_1 to pressure p_2 along line AB and thereafter the discharge of the compressed air 45 along line BC (Fig. 2). After the scavenging and exhaust ports 3, 4 have been uncovered by the motor pistons 2, the freely moving masses come to a standstill. The residual compressed air in 50 the dead spaces of the compressor cylinder 6, on which acts the pressure p_2 , in expanding along line CD (Fig. 2) down to the suction pressure p_1 , now forces the freely moving masses again towards each other (return stroke), while at the same time (line DA) fresh air is sucked through 55 the suction valves 7 into the compressor cylinders. The compressed air discharged during the working stroke through the pressure valves 8 flows through the pipe 10, after the scavenging ports 3 have been uncovered by one of the motor 60 pistons 2, into the motor cylinder 1, at the same time displacing the exhaust gases through the exhaust ports 4 and filling the motor cylinder with fresh air under the pressure p_2 . In the exhaust gas conduit 11 communicating with the exhaust ports 4 of the motor is provided a pressure 65 regulating member 20, which determines the scavenging pressure in the motor and consequently also the discharge pressure p_2 in the compressor. The waste gases and the scavenging air 70 in excess discharged through the exhaust ports 75

4 are fed to a secondary engine, for instance a turbine (not shown) to do useful work therein.

For the purpose of regulating the quantity and amount of energy in the driving gas furnished by the driving gas generator, the suction pressure p_1 and delivery pressure p_2 in the compressor are varied. For the variation of the suction pressure there is for instance provided at each suction chamber 18 of the compressor a slide 12, which is adjustable manually or automatically, for instance in dependency from the load on the secondary engine. This is shown in Fig. 1, in which the centrifugal governor 40 of a secondary engine (not shown) is provided with a sleeve 41, to which corresponding to the two slides 12 toward both sides two rods 42, 43 are linked. The other ends of these rods are linked to the free ends of the legs 44, 45 of the bell cranks arranged for rotation about the points 46, 47. The free ends of the legs 48, 49 of the bell cranks are 20 linked to the rods 50, 51. These rods 50, 51 are connected through the fulcrums 52, 53 with the rods 56, 57 guided at 54, 55, these rods being directly connected to the slides 12. The positions of the governor and the rods, shown in full lines, 25 illustrate the positions with higher numbers of rotation, i. e. with smaller load on the secondary engine, while on the left hand side of the governor the dashed lines indicate the positions of the governor sleeve and the rods with smaller numbers of rotation, i. e. with higher load on the secondary engine. In the latter case e. g. the fulcrum 52 has been displaced toward 58. About the length of this distance 52—58 also the slide 30 has been lifted. Hereby the throttling of the suction air has been reduced in a manner such that a higher output of the compressor portion and also 35 of the motor portion of the free piston engine is effected. When the inlet is throttled, i. e. when the suction pressure p_1 is low, there is obtained 40 the compressor diagram A'B'C'D'A' drawn with dash lines in Fig. 2, with the delivery pressure p_2 . The variation of the delivery pressure in such manner that the pressure ratio in the compressor remains approximately constant, is effected by means of the pressure regulating member 45 20 provided in the conduit 11, which is illustrated in section in Fig. 6. The waste gas conduit 11 is closed by a slide 22 formed with a passage 21, and operated by a piston 23. The gases in 50 the conduit 11 pass through a boring 24 below the lower ring-shaped piston surface 25, so that this surface is acted upon by the pressure of the combustion gases escaping from the motor cylinder and of the scavenging air in excess, i. e. 55 with the pressure p_2 or p_2' , while the upper surface 26 of the piston 23 is placed under the suction pressure p_1 or p_1' , since the space above the piston 23 is connected through pipes 27, 17 with the suction chamber 18. The atmospheric pressure 60 acting on the slide face 28 is counteracted by the spring 29 acting from above on the piston 23, this spring being so dimensioned that a small excess of force tends to shift the pressure regulating member 22, 23 downwardly into closing 65 position. The surface ratio of the two surfaces 24 and 26 is so chosen that on the pressure p_2 being attained, the pressure regulating member is lifted counter to the pressure p_1 on the piston surface. However, if the suction pressure p_1 70 is throttled, for instance down to p_1' , the correspondingly lower delivery pressure p_2 suffices already to open the pressure regulating member, so that thus the ratio of the pressures $p_1:p_2$ remains always approximately constant, since the 75

surface ratio is approximately in the reversed proportion of these pressures.

The waste gases and the scavenging air, in excess, flow through the piping 30 to the secondary engine, for instance a turbine, (not shown).

In the diagram according to Fig. 2 the feed-back energy, which is liberated in the compressor cylinder and brings about the return stroke, is represented at a high suction and delivery pressure of the compressor by the surface CDAFEC and, in the case of the reduced pressures p'_1 , p'_2 , by the considerably smaller surface C'D'A'FEC'. According to Fig. 3 the compression in the motor cylinder begins in the first case (high compressor pressures) at the pressure p_2 and ends at the pressure p_3 , the compression work is represented by the surface GHJKG; in the second case the compression in the motor cylinder begins at the lower pressure p'_2 and ends at the pressure p'_3 ; in correspondence therewith also a lower compression energy corresponding to the surface G'H'JKG' must be brought into action. Thus the compression ratio in the motor (in the first case $p_3:p_2$ and in the second case $p'_3:p'_2$) is at least approximately equal in both cases, i. e. it remains practically constant during all variations of the initial compressor pressure.

When the compressor piston 5 has a larger diameter than the motor piston 2, so that on the rear side 13 of the compressor piston 5 there remains over an effective piston surface equal to the difference between the compressor piston surface and the motor piston surface, this differential surface must, during the return stroke, produce a displacement energy, which must be subtracted from the feed-back energy CDAFEC liberated in the compressor cylinder, in order to obtain the energy still available for the compression of the motor charge. In order now, that in regulating steps i. e. when varying the pressures arising in the compressor and the feed-back energy to be produced by the compressor, the permanently constant pressure ratio in the motor be attained, I load also the differential surface with a regulatable pressure, for instance the suction pressure of the compressor. In the two instances of regulation here in view there now result, according to Fig. 4, different amounts of displacement energy to be produced by the differential surface, viz. in the first case (loading with the compressor suction pressure p_1) the amount represented by the surface LMNOL, in the second case (loading by the compressor pressure p'_1) the amount corresponding to the surface L'M'NOL'. There are therefore available as feed-back energies:

In the first case:

surface CDAFEC—surface LMNOL=

surface GHJKG and

In the second case:

surface C'D'A'FEC'—surface L'M'NOL'=

surface G'H'JKG'

Since the amounts of energy to be deducted (LMNOL and L'M'NOL') vary in the same proportion as the amounts of energy liberated in the compressor, the pressure ratio in the motor ($p_2:p_3$) remains at least approximately constant. In order to realize this mode of operation, it is only necessary, in the arrangement according to Fig. 1, to bring the space 14 covered by the differential surface 13 into permanent communication, by means of a conduit, with the space 18

between the throttle slide 12 and the suction valves 1.

Instead of placing on the differential surface 13 a load which remains equal throughout the stroke, according to line LM or L'M', I may also place thereon a load which changes, according to certain laws, for instance an alternating compression and expansion of the gas in the space 14 according to Fig. 5 which follows the line LQ for the first, and the line L'Q' for the second 10 of the two regulating instances mentioned above. To this end there is connected with the compressor piston 5 a slide 19 which uncovers an aperture 16 formed in the cylinder wall, which communicates with the suction chamber 18 15 through the conduit 17, when the freely moving mass has reached its extreme end position (between the end of the working stroke and the start for the return stroke). I thus obtain that in this end position the same pressure prevails 20 in the space 14 as in the space 18; on the apertures 16 having been closed, when the return stroke begins, there now takes place a compression in the space 14 according to line LQ or L'Q', while during each subsequent working 25 stroke an expansion takes place along the same line.

In the example just described the suction pressure p_1 in the compressor thus forms the lower end pressure (point L or L') of the compression-expansion line for the space 14. Instead of this, also one of the regulating pressures (either the suction pressure p_1 or the delivery pressure p_2) may form the upper end pressure of a compression-expansion line. In that case the aperture 35 16 should be controlled in such manner that the space 14 communicates with the space 18 through conduit 17 not, as above, during the outer dead centre position of the piston (between the end of the working stroke and the start of the return 40 stroke), but during the inner dead centre position (between the end of the return stroke and the start of the working stroke). However, if the delivery pressure p_2 is chosen as end pressure, then during the inner dead centre position 45 the space 14 must be made to communicate with the delivery conduit 10 of the compressor.

The quantity of fuel to be fed per cycle into the motor cylinder through the nozzle 9, should be chosen in accordance with the quantity of air, 50 which is regulatable according to this invention, in the motor cylinder. The regulation of the quantity of fuel may also be influenced in a well known manner in dependency from the regulating pressures (suction pressure p_1 or delivery 55 pressure p_2).

Fig. 7 illustrates diagrammatically a free piston motor compressor provided with a single reciprocating free piston, the same reference numerals being used as in Fig. 1. According to Fig. 60 7, a buffer or compensating cushion chamber is provided, which comprises the piston 35 and the cylinder space 36. The space 36 constitutes a boring in the reciprocating free piston 2, 5, while the piston 35 is stationary. The movement of 65 the free piston 2, 5 causes the content of the cylinder space 36 to be alternately compressed and expanded. The amount of energy stored in this manner in the buffer space 36 during the working (upward) stroke of the motor piston 2 70 is again delivered during the return (downward) stroke of the piston to the free pistons, in a manner known in itself, for the purpose of supplementing the amount of energy deriving from the dead space of the compressor.

Fig. 8 shows a longitudinal section, drawn to a larger scale, through the motor cylinder 1 shown in Fig. 7. The reference numerals are the same as in Fig. 7. Two slots 3 are provided as inlet for the compressed air, while the combusted gases are delivered from the motor cylinder space first through the preliminary delivery slots 4' and subsequently through the main delivery slots 4. There are shown two of each of these delivery slots. The inlet and delivery slots are controlled, in a known manner, by means of the motor piston 2. The arrows shown in Fig. 8 represent the direction of current of the compressed air or the combusted gases, respectively.

15 I wish it to be understood that I do not desire to be limited to the exact details of construction shown and described for obvious modifications will occur to a person skilled in the art.

I claim:—

20 1. A free piston motor compressor, in which the compressed air produced in the compressor serves as scavenging and charging air for the motor, comprising in combination, a motor cylinder, a compressor cylinder, a free piston in said motor cylinder and a free piston in said compressor cylinder, said pistons being rigidly connected with each other, means for conducting compressed gas from said compressor cylinder into said motor cylinder and means for varying the 25 suction and delivery pressures in said compressor cylinder, while keeping the ratio of the two pressures approximately constant.

25 2. A free piston motor compressor comprising in combination, a motor cylinder, a compressor cylinder, a free piston in said motor cylinder and a free piston in said compressor cylinder, said pistons being rigidly connected with each other, said compressor piston having a larger diameter than said motor piston, means for causing the 30 suction pressure prevailing in said compressor to act on the rear face of said compressor piston, means for conducting compressed gas from said compressor cylinder into said motor cylinder and means for varying the suction and delivery pressures in said compressor cylinder, while keeping the ratio of the two pressures approximately 35 constant.

35 3. A free piston motor compressor comprising in combination, a motor cylinder, a compressor cylinder, a free piston in said motor cylinder and a free piston in said compressor cylinder, said pistons being rigidly connected with each other, said compressor piston having a larger diameter than said motor piston, means for causing the 40 suction pressure prevailing in said compressor to act on the rear face of said compressor piston, means for conducting compressed gas from said compressor cylinder into said motor cylinder, means for varying the suction and delivery pressures in said compressor cylinder, while keeping the ratio of the two pressures approximately 45 constant, and means for causing the pressure prevailing in the part of said compressor cylinder covered by the rear side of said compressor piston to vary according to a compression-expansion line, the initial pressure of which is determined by one of the pressures prevailing in said compressor.

40 4. A free piston motor compressor comprising in combination, a motor cylinder, a compressor cylinder, a free piston in said motor cylinder and a free piston in said compressor cylinder, said pistons being rigidly connected with each other, said compressor piston having a larger diameter than 45 said motor piston, means for causing the suction

pressure prevailing in said compressor to act on the rear face of said compressor piston, means for conducting compressed gas from said compressor cylinder into said motor cylinder, means for varying the suction and delivery pressures in said compressor cylinder, while keeping the ratio of the two pressures approximately constant, and means for causing the pressure prevailing in the part of said compressor cylinder covered by the rear side of said compressor piston to vary according to a compression-expansion line, the end pressure of which is determined by one of the pressures prevailing in said compressor.

5 5. A free piston motor compressor comprising in combination, a motor cylinder, a compressor cylinder and free pistons rigidly connected with each other and arranged in said cylinders for free reciprocation, said motor cylinder being formed with an exhaust port, an exhaust gas 20 conduit arranged to the rear of said exhaust ports, a regulating device inserted in said conduit, a piston-shaped control member forming part of said device and formed with two piston surfaces, one surface being adapted to be acted 25 upon by one, the other surface by the other regulating pressure arising in said engine, these controlling surfaces being dimensioned at a ratio which is approximately the reverse of the ratio of said regulating pressures.

30 6. A free piston motor compressor comprising in combination, a motor cylinder, a compressor cylinder and free pistons rigidly connected with each other and arranged in said cylinders for free reciprocation, said motor cylinder being 35 formed with an exhaust port, an exhaust gas conduit arranged to the rear of said exhaust ports, a regulating device inserted in said conduit, a piston-shaped control member forming part of said device and formed with two piston surfaces, one surface being adapted to be acted 40 upon by one, the other surface by the other regulating pressure arising in said engine, these controlling surfaces being dimensioned at a ratio 45 which is approximately the reverse of the ratio of said regulating pressures, and means whereby the space in said compressor cylinder covered by the rear face of said compressor piston is arranged to be permanently acted upon by the suction pressure in said compressor.

35 7. A free piston motor compressor comprising in combination, a motor cylinder, a compressor cylinder and free pistons rigidly connected with each other and arranged in said cylinders for free reciprocation, said motor cylinder being 50 formed with an exhaust port, an exhaust gas conduit arranged to the rear of said exhaust ports, a regulating device inserted in said conduit, a piston-shaped control member forming part of said device and formed with two piston surfaces, one surface being adapted to be acted 55 upon by one, the other surface by the other of the regulating pressure arising in said engine, these controlling surfaces being dimensioned at a ratio which is approximately the reverse of the 60 ratio of said regulating pressures, and a controlling member connected with said pistons and connecting the space in said compressor cylinder covered by the rear face of said compressor piston during the outer dead centre position of said 65 piston with the suction space of said compressor.

8. A free piston motor compressor comprising in combination, a motor cylinder, a compressor cylinder and free pistons rigidly connected with each other and arranged in said cylinders for 70 75

free reciprocation, said motor cylinder being formed with an exhaust port, an exhaust gas conduit arranged to the rear of said exhaust ports, a regulating device inserted in said conduit, a piston-shaped control member forming part of said device and formed with two piston surfaces, one surface being adapted to be acted upon by one, the other surface by the other regulating pressure arising in said engine, these 5 controlling surfaces being dimensioned at a ratio which is approximately the reverse of the ratio of said regulating pressures, and a control member, which connects the space in said compressor cylinder covered by the rear face of said 10 compressor piston during the inner dead centre position of said piston with the suction space of said compressor.

9. A free piston motor compressor comprising in combination, a motor cylinder, a compressor cylinder and free pistons rigidly connected with 15

20

each other and arranged in said cylinders for free reciprocation, said motor cylinder being formed with an exhaust port, an exhaust gas conduit arranged to the rear of said exhaust ports, a regulating device inserted in said conduit, a piston-shaped control member forming part of said device and formed with two piston surfaces, one surface being adapted to be acted upon by one, the other surface by the other regulating pressure arising in said engine, these 5 controlling surfaces being dimensioned at a ratio which is approximately the reverse of the ratio of said regulating pressures, and a control member, which connects the space in said compressor cylinder covered by the rear face of said compressor piston during the inner dead centre position of said piston with the delivery conduit of the compressor.
